CAR WHEEL UNIT

Horace Lyndon Keyes, Los Angeles, Calif., assignor to
H & S Metal Products Co., Los Angeles, Calif., a cor-
poration of California

Filed Oct. 19, 1959, Ser. No. 57,977

Term of patent 14 years

(Cl. D14—30)

Fig. 1 is a front elevation of a car wheel unit embodying my new design;

Fig. 2 is a perspective view of the car wheel unit of Fig. 1; and

Fig. 3 is a sectional view taken along line 3—3 of Fig. 1.

My design for a car wheel unit is characterized by the saddle-shaped spokes on the deeply recessed face, which radiate from the center hub to the sidewalls, all as shown.

I claim:

The ornamental design for a car wheel unit, substan-
tially as shown and described.
